MANUALLY CONTROLLED REFLECTIVE PIN-BALL GAME CABINET

Ronald D. Halliburton, Miami, Fla., assignor to Allied
Leisure Industries, Inc., Hialeah, Fla.

Filed Feb. 17, 1972, Ser. No. 227,341

Term of patent 14 years

Int. Cl. D21—01

U.S. Cl. D34—5 JJ

FIG. 3

FIG. 2

FIG. 1

FIG. 4

FIG. 5

FIG. 1 is a front elevation of a manually controlled reflective pin-ball game cabinet in reduced scale, showing my new design.

FIG. 2 is a side elevation thereof.

FIG. 3 is a top plan view thereof.

FIG. 4 is a rear elevation thereof.

FIG. 5 is a bottom plan view thereof.

The side not shown is the same as that shown in FIG. 2.

I claim:

The ornamental design for a manually controlled reflective pin-ball game cabinet, as shown and described.
